LATCH FOR WINDOW OPERATORS

Adolph E. Strom, Portland, Oreg.

Application September 19, 1935, Serial No. 41,327

1 Claim. (Cl. 16—195)

This invention relates to a window construction and it aims to provide means whereby the sashes are slidably mounted with the elimination of weights, cords, pulleys and hardware such as is used at present on double hung sashes. Aside from the cost of the parts mentioned, the cost of window frames is likewise reduced inasmuch as pockets therein are not required.

It is further aimed to provide such a construction which will eliminate weather-stripping, rattling of windows, render the window burglar-proof in closed position, and cause one sash to raise as the other lowers, through movement of the other.

The more specific objects and advantages will become apparent from a consideration of the description following taken in connection with accompanying drawing illustrating an operative embodiment.

20 In said drawing:—

Figure 1 is a view of an improved window construction according to the invention in front elevation, partly broken away;

Figure 2 is an enlarged vertical sectional view 25 taken on the line 2—2 of Figure 1;

Figure 3 is a horizontal sectional view taken substantially on the line 3—3 of Figure 1;

Figure 4 is a horizontal sectional view taken on the line 4—4 of Figure 1; and

30 Figure 5 is a horizontal sectional view taken on the line 5—5 of Figure 4.

Referring specifically to the drawing, 10 designates a conventional window frame in which a pair of relatively slidable sashes 11 are mounted by usual stops or otherwise as at 12, such sashes carrying lights 13.

Countersunk in the inner surfaces of the side stiles or uprights 14 of the window frame 10 are plates 15, the same having flanges 16 through 40 which screws or other fastenings 17 are passed to secure the plates in place. Journalized in said plates 15 is a rotatable shaft 18 which is disposed between the meeting rails of the sashes 11. Keyed to such shaft 18 are pinions 19 enmeshed 45 with rack bars 20 screwed or otherwise secured as at 21 to the sashes. Obviously, the rack bars 20 may be made of cast metal or rolled, or otherwise as preferred, and the pinions 19 may be made of any suitable material such as cast iron, copper, 50 steel, fibre, brass, aluminum, or bakelite.

As a result of the construction described, one sash will raise as the other sash lowers, upon

sliding either sash, thus simultaneously opening the window at the top and bottom, or simultaneously closing them at the top and bottom.

The sashes are ordinarily locked against movement in closed position and in any of the 5 open positions through the engagement of a latch 22 between teeth of one of the pinions 19. Such latch is preferably pivoted as at 23 within a slot 24 of one of the plates 15. A leaf spring 25 fastened to the last mentioned plate as at 26, 10 is engaged with one end of the latch 22 to prevent displacement thereof and urge closing movement.

Said latch 22, however, may be raised or disengaged from the adjacent pinion 19 in order to 15 permit the sashes to slide and to this end an operating rod 27 is slidably mounted in the last mentioned plate 15 in a recess 28 thereof as well as slidably mounted through the adjacent part of the frame 10. Operator or rod 27 has a knob 20 29 at one end thereof and at its other end has a cam 30. When the rod 27 is pulled forward the cam 30 through engagement with the latch 22, elevates such latch out of engagement with the pinion 19, and holds it in that position so that 25 the sashes may be adjusted. The rod 27, however, after adjustment is adapted to be pushed inwardly, thus moving the cam 30 from beneath the latch 22 and the latter reengaging the pinion 19 through the urgency of the spring 25. 30

Various changes may be resorted to, provided they fall within the spirit and scope of the invention.

What is claimed is:—

In combination with a window-operator shaft 35 having a pinion thereon, a plate disposed in parallelism to the pinion and in which one end of said shaft is journaled, said plate having a slot extending therethrough, a latch in said slot engageable between the teeth of said pinion, means 40 pivoting the latch to the plate, a spring leaf secured to one side of the plate crossing said slot and engaging one end of the latch to urge the latch into engagement with said pinion, said plate having a slot therethrough disposed at a 45 right-angle to the first mentioned slot and opening at the base of the latter, and an operating member operable in the second mentioned slot having a cam engageable with the latch to disengage the latter from the pinion. 50
